CURRENT LIMITING DEVICE FOR LENARD
TUBES

Louis Frederick Ehrke, Newark, and Charles Morse Slack, Bloomfield, N. J., assignor to Westinghouse Lamp Company, a corporation of Pennsylvania

Application February 14, 1930, Serial No. 428,271

2 Claims. (Cl. 250—27.5)

The present invention relates to Lenard ray tubes and more particularly to current limiting means embodied in such tubes to protect the window thereof.

5 The inherent weakness of the Lenard ray tube lies in the fact that a single surge of high current may destroy the window.

Such destruction of a window necessitates nearly complete rebuilding of the tube since the operations such as, evacuating the tube, degasifying of metal parts and removing impurities have to be repeated in addition to the replacement of the window itself. The windows are extremely thin and difficult to construct and mount in the tube. 15 In addition any shielding means such as a metallic coating deposited on the window has to be reformed.

An object of our invention is to provide an improved Lenard ray tube in which a space charge 20 at the cathode will limit the electron current to such a value that the window will not be injured regardless of the filament temperature.

A further object of our invention is to provide a Lenard ray tube in which the cathode shall be 25 so shielded that the electron current will be limited to a safe value for a wide voltage range.

In carrying out our invention we provide a shielding means disposed about the cathode in such a manner and at a potential such that the 30 electron current of the tube will be limited to a value such that it cannot injure the window.

For a better understanding of our invention reference may be had to the accompanying drawings in which,

35 Fig. 1 is a central sectional view of a Lenard ray tube embodying our invention, and

Figs. 2 and 3 are fragmentary sectional views of other embodiments of our invention which may be substituted for the corresponding parts 40 in the tube shown in Fig. 1.

Similar numerals refer to similar parts throughout the several views.

The Lenard ray tube shown in Fig. 1 comprises a bulb 5, a hollow anode 6 and a filamentary cathode 7. The cathode 7 is mounted in a double walled reentrant stem 8 formed at one end of the envelope 5 and a pair of leading-in conductors 9 are sealed in a press 10 at the outer end of said reentrant stem 8. The inner end 11 of stem 8 is closed thus providing a space 12 between the walls of the stem which space is sealed from the interior of the envelope 5 and open to the exterior thereof. The inner surface of stem 8 which borders the space 12 may be provided with a coating 13 of metal such as gold, silver or aluminium

in the form of a thin layer deposited thereon. Tin foil or other suitable conductive material may also be used for the metallic coating 13. One of the cathode leading in conductors 9 is electrically connected to the metallic coating 13 at point 14.

In many instances the metallic coating 13 may be omitted from the stem 8 since the cathode leading-in conductors 9 will increase the ionization of the air in the space 12 and render the same conducting. The column of air in space 12 will then function as a conductor and induce a charge of the same potential as that of the leading-in conductors 9 to the walls of the stem 8 adjacent the cathode to shield the same. The metallic coating on the stem 8, however, appears to render the operation of the tube more constant. At the end of envelope 5 opposite the reentrant stem 8 a neck 16 is formed in which the hollow anode 6 may be supported by a suitable split sleeve 17. A press 18 is formed in the neck 16 at a point adjacent the side of the hollow anode 6 and a leading-in conductor 19 for said anode 6 is sealed in this press.

At the outer end of the neck 16 a window 20 permeable to Lenard rays is constructed in accordance with the disclosure of Patent 1,735,302 assigned to the same assignee as the present invention.

Briefly this window 20 comprises a bulbous body 21 of vitreous material of relatively heavy construction having a concentric reentrant portion 22, said reentrant portion 22 having at the center thereof a thickness of from about 0.0001 to 0.005 inches.

The reentrant stem 8, the hollow anode 6 and the window 20, are disposed in alignment along the central longitudinal axis of the envelope 5, so that when a low potential is impressed on the cathode leads 9 to bring the cathode 7 to incandescence and a high potential is impressed on the cathode and anode, electrons will be emitted by cathode 7 and directed through the hollow anode 6 and window 20.

According to the present invention the reentrant stem 8 together with its metallic coating 13 serves a three-fold purpose because of the electrical connection between the coating 13 and one of the cathode leading-in conductors 9, and the disposal of the cathode 7 within said reentrant stem. First, said reentrant stem and coating focus the stream of electrons to a suitable sized spot on the window or a target beyond the window; second, they shield said cathode so that elec-

trical discharges originating at the cathode and tending to puncture the envelope when high voltage is applied will not occur and third, by virtue of their arrangement with respect to the 5 cathode they limit the current to such a value that the window of the tube will at all times be protected. To this end the cathode 7 is withdrawn into the bore of the reentrant tube a distance approximately three and one half times the diameter 10 of the bore of said reentrant stem.

In this construction the space charge at the cathode 7 afforded by the coating 13 which is at the same potential as the cathode will limit the electron current to a value which does not injure 15 the window regardless of the filament temperature.

For example, we have found that by placing the filament at a depth of about 2 cm. in a focusing cup 7 mms. in diameter that the electron current 20 was limited to approximately 0.1 ma., a reasonable value for the window.

A similar result can be obtained by placing a diaphragm of the correct size over the mouth of focusing cups now in general use. Such a construction is illustrated in Fig. 2 in which 25 is a focusing cup and 26 a filamentary cathode therein supported by leading-in conductors 27. A press 28 at the end of a stem 30 seals in the leading-in conductors 27. A sleeve 29 is secured to the outside 30 of press 28 and its supporting stem 30 and extends inwardly to the mouth of focusing cup 25. A metallic ring 31 may be used to supplement the support of focusing cup 26 and electrically connect said focusing cup to the sleeve 29. Cathode 35 26 is electrically connected to the focusing cup 25 through a conductor 32 leading to one of the leading-in conductors 27. A second sleeve 33 split through a part of its length by opposed slots 34 is mounted on the outside of sleeve 29 making a 40 sliding fit therewith. A diaphragm 35 closes the inner end of sleeve 33 except for a central opening 36 therein.

In this construction the ratio of the depth of the filament from the diaphragm to the diameter 45 of the diaphragm opening 36 may be adjusted by tapping the ends of the tube since this adjusts the positions of sleeves 29 and 33 relative to each other. In this way the limiting value of the electron current may be adjusted as desired.

Referring to Fig. 3 a further embodiment of 50 our invention is illustrated in which a fixed ratio between the filament depth and the focusing cup diameter is obtained to restrict the electron current to a fixed limiting value. In this embodiment a focusing cup 25' contains a cathode filament 26' disposed at a depth of about three and a half times the bore of the focusing cup. Leading-in conductors 27' and sleeve 29' support the cathode filament 26' through the intermediary 55 of conductor 32' and metal ring 31' in the same manner as described relative to the corresponding elements in the device shown in Fig. 2.

A press 28' on stem 30' forms a support for the sleeve 29' as before. Numeral 6 in Figs. 2 and 3 60 designates in broken lines a portion of the anode shown in full in Fig. 1.

The current limiting means according to our

invention is applicable to a wide range of voltages impressed upon the tube. Although the current of the tube increases as the voltage increases the absorption of energy by the window affords a compensating factor. As disclosed in the Slack Patent 1,735,302, above referred to, the absorption of energy by the window of the tube varies with the voltage, decreasing as the voltage increases. Thus for instance with a glass window of about 0.00025 inch thickness, it requires a potential of about 26,000 volts between the anode and cathode 80 to cause the most of the cathode rays to just get through the window. At this voltage all of the energy of the electron is absorbed by the glass which, as a consequence heats up. As the voltage applied between the electrodes increases, however, the loss of energy in the glass window decreases rapidly.

With a velocity of the electron corresponding to 60,000 volts the 0.00025 inch glass window will transmit electrons with an emergent velocity corresponding to 54,000 volts, there being a loss of velocity in the window corresponding only to about 6,000 volts. Thus for instance, the same 90 thickness of glass will absorb only about 3,000 100 volts with an impressed potential 100,000 volts.

This decrease in energy loss in the glass, at higher voltages, effects a corresponding decrease in the heating effect of the glass. It thus becomes necessary to protect the window only against 105 heavy surges of current.

The invention has been described specifically in connection with a Lenard ray tube, but it is to be understood that the current limiting means is applicable to other devices and that the invention 110 is not limited to the exact construction shown but various modifications and changes may be made therein without departing from the invention as defined in the appended claims.

What is claimed is:

1. A Lenard ray tube comprising an envelope, a source of electrons therein, a window in said envelope permeable to high velocity electrons, an anode for directing a stream of high velocity electrons against said window, a reentrant stem in 120 the form of a double walled hollow sleeve surrounding and extending beyond said source of electrons a distance of approximately three and a half times the bore of said sleeve, said sleeve having a space open to the exterior of the envelope and closed to the space therein, and a metallic shield disposed in the open space and electrically connected to said source of electrons.

2. An electric discharge device comprising an envelope, a source of electrons therein, a window in said envelope permeable to high velocity electrons, an anode for directing a stream of high velocity electrons against said window, a reentrant stem in the form of a double walled hollow sleeve surrounding and extending beyond said 130 source of electrons a distance approximately three and one half times the bore of said sleeve, said sleeve having a space open to the exterior of the envelope and closed to the space therein.

LOUIS FREDERICK EHRKE,
CHARLES M. SLACK.
